UNITED STATES PATENT OFFICE

2,160,639

WATER COOLER

Ralph E. Billings, Fort Wayne, Ind., assignor to
General Electric Company, a corporation of
New York

Application May 6, 1938, Serial No. 206,442

7 Claims. (Cl. 62—141)

My invention relates to liquid cooling apparatus and more particularly to liquid coolers of the mechanically cooled type.

The objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a view partly in section of a water cooler embodying my invention and Fig. 2 illustrates, schematically, a possible electrical control system and refrigerating circuit applied to a water cooler embodying my invention.

In accordance with my invention I have provided a liquid cooling apparatus 10 containing a cooling chamber 11 and a cylindrical cooling coil 12 located in chamber 11. A distributing baffle 13 is supported upon the upper portion of the cooling coil 12 to direct the flow of the liquid to be cooled which enters chamber 11 through an inlet conduit 14 to the sides of chamber 11 in order that the liquid will be in close heat exchange relationship to cooling coil 12 in its downward flow. A substantially cylindrical baffle 15 is supported within the cooling coil 12 in spaced relation with respect to distributing baffle 13. The provision of this space between the two baffles permits free circulation of the liquid to be cooled between the inside and the outside of the lower baffle. I have found that this arrangement of baffles increases the capacity of the cooling coil and also the amount of liquid which can be drawn from the cooler before the outlet temperature rises above a given temperature.

The casing of the cooling apparatus 10 comprises an inner shell 16 with a bottom plate 17 suitably attached thereto as, for example, by welding and an outer shell 18 having a cover 19 and a bottom 20 suitably attached thereto, as by welding, for example. Heat insulation 21 is arranged between the inner and outer shells. The liquid to be cooled is fed into the cooling apparatus through inlet conduit 14 into the upper portion of chamber 11. The cooled liquid is withdrawn from the cooling chamber 11 through an outlet tube 22 which extends downwardly near the bottom of the cooling chamber 11. A hole 23 is provided in outlet conduit 22

to permit the escape of air which may have been entrapped in the cooling chamber 11.

The cooling coil 12, having a slightly less diameter than the inner shell 16, is assembled within the inner shell. The lower end of cooling coil 12 is joined to the bottom of a header 24 by means of a feeder tube 25. A small injector tube 26 extends downwardly through the top of the header 24 and the feeder tube 25 into the bottom turn of cooling coil 12. The upper end of the cooling coil is connected to the upper portion of the refrigerant header 24 by means of a conduit 27. Liquid refrigerant is conducted into the apparatus through injector tube 26 and feeder tube 25 into the cooling coil where the heat from the liquid to be cooled is absorbed, thus vaporizing the refrigerant. The vaporized refrigerant passes from the upper portion of the cooling coil 12 through conduit 27 into the refrigerant header 24 from which the vapor may be drawn off through conduit 27a.

The distributing baffle 13 is supported substantially horizontally on the upper turn of cooling coil 12 by a plurality of spring spacers 28, the convolutions of which fit between the convolutions of cooling coil 12. The substantially cylindrical baffle 15 is assembled within cooling coil 12 and extends up to a relatively small distance from the distributing baffle 13. Baffle 15 is supported by a plurality of clips 29 suitably secured to baffle 15. The clips 29 are attached to the lower turn of the spacer springs 28.

The liquid to be cooled enters the cooling chamber 11 through inlet conduit 14, spreads across distributing baffle 13 and flows or circulates downwardly along the inner shell 16 and over the cooling coil 12. The liquid then flows upwardly inside of baffle 15 and through the space between distributing baffle 13 and baffle 15 and down across the cooling coil 12. Thus, by reason of the cooperation between the distributing baffle 13 and the cylindrical baffle 15, a liquid circulation is set up which constantly causes the liquid to be cooled to recirculate through the space between the distributing baffle 13 and baffle 15 and thence downwardly into proximity with the cooling coil 12. A drain conduit 30 is provided in the bottom portion of the cooling chamber 11.

A thermostatic bulb 31 arranged within a casing 32 extends into the cooling chamber 11 thus providing a means to control operation of the refrigerating apparatus.

Referring to Fig. 2, I have shown in schematic form a cooling chamber 10 provided with liquid inlet and outlet 14 and 22 respectively and a liquid refrigerant inlet 26 and refrigerant vapor outlet 27a. The vaporized refrigerant is withdrawn into compressor 33. After compression, compressed refrigerant is discharged into condenser 34 and the liquid refrigerant is received in liquid receiver 35 from which the liquid refrigerant is returned to the cooling coil through conduit 26. Compressor 33 may be driven by an electrical motor 36 in any suitable manner as, for example, by means of pulleys 37 and 38 and belt 39. The electrical circuit comprises a source of electrical energy 40, supply lines 41 and control switch 42. Control switch 42 is opened and closed, thereby supplying or cutting off electrical energy at the motor 36, according to the temperature of the liquid within the cooling chamber 11 as measured by thermostatic bulb 31.

While I have shown a particular embodiment of my invention in connection with a liquid cooler, I do not desire my invention to be limited to the particular construction shown and described and I intend in the appended claims to cover all modifications within the spirit and scope of my invention.

What I claim as new and desire to secure by Letters Patent of the United States is:

30 1. A liquid cooling apparatus having inlet and outlet conduits for a liquid to be cooled, cooling means, distributing means beneath said inlet for causing said liquid to be cooled to circulate in proximity to said cooling means, and baffle means within said cooling means spaced from said distributing means in such a manner as to cause said liquid to be cooled to be recirculated into proximity with said cooling means.

40 2. In liquid cooling apparatus having a cooling chamber and inlet and outlet conduits for a liquid to be cooled, a cooling unit in said chamber, a distributing member for causing said liquid to be cooled to circulate in proximity to said cooling unit, said distributing member being arranged near the upper portion of said cooling unit and a baffle member arranged within said unit and spaced from said distributing means in such a manner as to cause said liquid to be cooled to be recirculated into proximity with said cooling unit.

45 3. In a liquid cooling apparatus, the combination of a cooling chamber having inlet and outlet conduits for a liquid to be cooled, a cooling coil in said chamber, a substantially horizontal distributing member for causing said liquid to be cooled to circulate in proximity to said cooling coil, said distributing member being arranged near the upper portion of said coil and a substantially cylindrical baffle member within said coil and spaced from said distributing means in such a manner as to cause said liquid to be cooled

to be recirculated into proximity with said cooling coil.

4. In liquid cooling apparatus, a cooling chamber, an inlet conduit for the liquid to be cooled disposed in the upper portion of said chamber, an outlet conduit for the cooled liquid, a cooling coil in said chamber, a substantially horizontal baffle member supported on the upper portion of said coil and beneath said inlet conduit, and a substantially cylindrical baffle member within said coil, said substantially cylindrical baffle member being supported by said coil in spaced relationship from said horizontal baffle member.

5 5. The combination of a liquid cooling chamber, an inlet conduit for the liquid to be cooled disposed in the upper portion of said cooling chamber, an outlet conduit for the cooled liquid, a cooling coil arranged in said chamber, a distributing baffle supported substantially horizontally beneath said inlet conduit, a substantially cylindrical baffle member arranged within said coil in such a manner as to leave a space between the upper edge of said baffle member and said distributor plate to permit free circulation of the liquid to be cooled between the inside and the outside of said cylindrical baffle member.

6. In liquid cooling apparatus, a cooling chamber, inlet and outlet conduits for a liquid to be cooled, cooling means, a substantially horizontal distributing means for causing said liquid to be cooled to circulate in proximity to said cooling means, said distributing means being arranged beneath said inlet and near the top of said cooling means, said distributing means being so shaped as to direct the liquid to be cooled into proximity with said cooling means, and baffle means within said cooling means spaced from said distributing means in such a manner as to cause said liquid to be cooled to be recirculated into proximity with said cooling means.

30 7. In combination with a liquid cooling chamber, an inlet conduit for liquid to be cooled disposed in the upper portion of said cooling chamber, an outlet for cooled liquid, a cooling coil within said chamber, a substantially horizontal distributing means beneath said inlet conduit and near the top of said cooling means, said distributing means having a configuration substantially the same as the configuration of a vertical projection of said cooling coil, whereby the liquid to be cooled will flow across the distributing means into proximity with said cooling means, and substantially cylindrical baffle means within said cooling means spaced below said distributing means in such a manner as to provide an opening between said distributing means and said cylindrical baffle to permit free circulation of the liquid to be cooled from the inside of said baffle means into proximity with said cooling means on the outside of said baffle means.

RALPH E. BILLINGS.
